JAMES W. FULLER, OF CATASAUQUA, PENNSYLVANIA, ASSIGNOR TO FULLER-LEHIGH COMPANY, OF FULLERTON, PENNSYLVANIA, A CORPORATION OF PENNSYLVANIA.

SAMPLING DEVICE FOR PULVERIZER-MILLS.

1,337,697.

Specification of Letters Patent.

Patented Apr. 20, 1920.

Application filed December 4, 1918. Serial No. 265,217.

To all whom it may concern:

Be it known that I, JAMES W. FULLER, a citizen of the United States, residing at Catasauqua, in the county of Lehigh, State 5 of Pennsylvania, have invented certain new and useful Improvements in Sampling Devices for Pulverizer-Mills; and I do hereby declare the following to be a full, clear, and exact description of the invention, such as 10 will enable others skilled in the art to which it appertains to make and use the same.

The present invention relates to improvements in pulverizer mills and is directed to the provision of a discharge spout for such 15 a mill which is so constructed as to permit of the convenient removal of samples of the pulverized material while it is being discharged from the mill.

The invention is herein shown as applied 20 to a Fuller pulverizer mill of the type shown, for example, in my United States Patents Nos. 849,779, 922,468 and 1,039,721. Pulverizer mills of that type have a pulverizing zone containing a race-way within which 25 operate the pulverizing balls actuated by a series of rotating radial pushers, and the pulverized material is removed upwardly from the pulverizing zone largely by the suction of rotating lifting blades which lift 30 the material into the field of a series of fan blades which float it against and through a cylindrical screen surrounding the upper part of the pulverizing chamber. After passing through the screen, the material falls 35 into a chamber from which it is discharged through a spout, and this spout usually leads to some kind of a conveyer for transferring the pulverized material to any desired locality.

40 The miller is obliged to take samples of the material discharged by the mill from time to time, in order to determine whether it is being pulverized to the proper degree of fineness. It has heretofore been customary 45 to provide a hole in the discharge spout and a removable cover for this hole. Machines of this general character are also provided with a platform near the top so that the miller may have easy access to the mechanism 50 for feeding the material to the mill and the devices for controlling the operation of the mill. Inasmuch as a mill of the type referred to above discharges some air with the finely ground material, it has 55 been a somewhat difficult matter to obtain

a sample from the hole in the discharge spout. Furthermore, since this spout is located underneath the miller's platform, it has been inconvenient to take samples and when the miller desired to do so, he was 60 obliged to leave the platform and thus had no supervision of the feed going to the mill or the operation of the mechanism. The miller might even be disposed to neglect to take the samples as often as he should, owing 65 to the inconvenience of getting down from the platform and the loss of control over the material going to the mill at such times.

In accordance with the present invention, I provide a discharge spout having a sampling pipe which permits the miller to take 70 samples while standing upon the platform. The sampling pipe is so constructed that all he has to do is to lift a lid closing the top thereof, insert a sampling receptacle which 75 generally consists of a small can attached to a rod, and after the can has received the necessary amount of material, it may be withdrawn from the sampling pipe and the lid closed. The sampling device also possesses 80 the advantage that there is no escape of dust or air when the lid is open. This is due to the fact that an air chamber is provided above the conveyer so that when the lid of the sampling pipe is lifted from its seat, air 85 is drawn in through the sampling pipe, instead of being blown out through it, and this causes all of the dust to be drawn along with the stream of material through the discharge spout into the conveyer. 90

Other advantageous features of the invention and the particular nature thereof will appear more clearly from the following detailed description of the preferred embodiment as illustrated in the accompanying 95 drawing, in which Figure 1 is an elevation of a pulverizer mill, partly in section to show the interior mechanism, while the discharge spout and sampling device of the present invention are shown in section, and Fig. 2 is 100 a plan view of the upper end of the sampling device with the cover thereof in closed position.

Referring to the drawing, 10 represents the base of the machine and 11 a standard 105 upon the top of which is a casing 12 surrounding the grinding mechanism. On top of the casing 12 is a frame 13 which supports the screen 14 through which the material is discharged. The frame has on its 110

top a removable cover plate 15 provided with a bearing member 16 in which is supported a vertical shaft 17 resting at its foot in a suitable bearing set in the base 10. 5 The shaft 17 is provided with a driving pulley 18 which may be connected to any suitable source of power. Upon the plate 15 is mounted a feeding device 19 which may be of any suitable construction adapted to feed 10 the material to the mill in any desired quantity, this feeding device being preferably provided with controlling mechanism whereby the miller may regulate the amount of material fed to the mill. 15 The upper end of the shaft 17 is preferably provided with a series of pulleys 20 and a second series of reversely arranged pulleys 21 is mounted upon a suitable support 22 attached to the cover plate 15. By shifting 20 the position of the belt 23 upon pulleys of different diameters, the speed of the feeder 19 may be regulated as desired. A platform 25 is mounted upon a frame-work comprising vertical columns 26 and horizontal girders 27, the platform being provided with hand rails 28. The platform should be of such a height as to permit the miller to conveniently reach the feeding device 19 and the speed control mechanism 25 mounted upon the top of the mill. The 30 platform is of course, provided with a stairway or ladder (not shown) leading to the floor. 35 Mounted within the interior of the casing 12 and resting upon the bottom 29 thereof is an annular concave grinding ring 30, and between this ring and the outer wall of the casing 12 is an annular passageway 31 opening at its upper end just outside of the 40 screen 14 and at its lower end opening into a chamber 32 beneath the casing 12, and from which pulverized material may be removed through a spout 33 attached to the side of the casing. The spout 33 is provided 45 with an upwardly extending portion 34 which is preferably formed integral with the portion 33 of the spout, and which forms the lower or base section of the sampling pipe. The upper portion of the sampling 50 pipe consists of a section 35 provided with a flange adapted to be bolted to a corresponding flange at the end of section 34. A gasket 36 formed of asbestos, or any other suitable material, should preferably be inserted between the two sections of the sampling pipe. The top of the section 35 is provided with a flange 37 having two pairs of diametrically opposite upstanding lugs 38. 55 A lid 39 is provided for covering the top of 60 the sampling pipe, and this lid is provided with a lug adapted to fit between the lugs of one pair 38 and to be permanently pivoted thereto by means of a suitable bolt 40. Diametrically opposite the first named lug is a 65 second lug adapted to enter between the lugs

of the opposite pair 38, and this lug on the cover may be attached to the fixed lugs by means of a bolt 41 which, however, should be arranged so that it may be removed whenever it is desired to lift the cover. It 70 will be understood that either one of the bolts may form the fixed pivot of the cover, while the fastening bolt may or may not be used, the weight of the cover holding it in place against any lifting tendency of air 75 within the discharge spout. In order to insure a tight fit of the cover upon the upper end of the sampling pipe, an inner cover or lining 42 of asbestos or any other suitable material, should be attached to the lower 80 face of the lid 39 as by rivets 43. Attached to the lower end of the discharge spout 33 is a pipe 45 leading to a suitable conveyer 46 which is here indicated as a screw conveyer, although any other suitable form of 85 mechanism for conveying away the pulverized material may be used. 90 The rotating portions of the apparatus are supported upon the shaft 17 and comprise a frame or yoke 47 provided at its lower end with radial arms to the outer ends of which are connected pusher members for engaging and driving the grinding balls 48 as the shaft is rotated. The radial arms are clearly shown in my patents referred to 95 above, but are not shown in the view of Fig. 1. The upper portion of the frame or yoke 47 carries a number of lifting blades 49, and above the lifting blades are radial fan blades, which do not appear in Fig. 1 since 100 they are within the casing 13, but are of a construction similar to that shown in these same patents. The shaft 17 also carries a sweep 51 provided with a number of vertical blades 52, the purpose of which is to agitate 105 the material in the chamber 32 and promote a more complete discharge through the spout 33.

In the operation of the apparatus, the shaft and moving parts are driven by a belt 110 passing over pulley 18 and the desired material is gradually supplied to the machine by the feeding mechanism 19 under the control of the miller who stands upon the platform 25. The screen 14 is of a mesh such as 115 to permit the passage therethrough of particles of the intended size. If in the material supplied to the upper portion of the machine, there are particles small enough to pass through the mesh of the screen, these 120 particles are driven out by the blades on the yoke, are caught by the outer wall surrounding the screen, and then fall through the passageway 31 into the chamber 32 from which they are discharged through the 125 spout 33 and the pipe 45 to the conveyer 46. Particles that are too large to pass through the screen fall into the pulverizing zone between the grinding ring and the balls where 130 they are reduced in size. The ground mate-

rial is elevated from the zone of operation of the grinding balls by the suction effect produced in the upper or screening chamber, where the particles are driven through 5 the screen 14 by the fan blades on the yoke. The inclined lifting blades 49 also aid in lifting material into the region of the fans. Any material lifted out of the grinding zone by the suction effect and which is still 10 too coarse to pass through the screen 14 finally falls again into the grinding zone and is subjected to another pulverizing operation. Ultimately all of the material which has been pulverized to the required 15 degree of fineness passes through the screen 14 and falls into the chamber 32 from which it is discharged into the spout 33 in a constant stream.

Whenever the miller desires to obtain a 20 sample of the material as it is being discharged from the mill, he lifts the lid 39 after removing the locking bolt 41, if such a bolt has been used. The lid may be then 25 swung about the bolt 40, and the miller inserts a sampling can through the spout and into the path of the material being discharged from the machine. When the can is filled, it is removed for examination and the lid is turned down to cover the end of 30 the sampling pipe. With the arrangement here shown, there is a down draft of air through the discharge spout into the conveyer, and hence when the sampling tube is open, air enters the top of the same, instead of being blown out; thus the escape 35 of any of the pulverized material or fine dust which fills the discharge tube is prevented and the miller may remove the samples without danger of having the material blown over him as might occur if the sample were removed through an aperture in the pipe 45 in accordance with the usual practice. The miller may thus obtain samples 40 conveniently and safely. If the locking bolt 41 is dispensed with, any convenient tool for lifting the lid 39 may be 45

used by the miller. Preferably the sampling receptacle is secured upon the end of a long rod by which it may be lowered into the sampling tube quite conveniently. 50 Thus it is unnecessary for the miller, in order to obtain a sample, to descend to the level below the platform 25 from which he cannot properly supervise the operation of the mill.

It will be understood that various changes may be made in the details of construction of my combined discharge spout and sampling device without departing from the principle of the invention.

I claim:

1. In a pulverizer mill having grinding mechanism and a chamber adapted to receive the material after it has been pulverized, the combination of a discharge spout 65 communicating with the chamber and comprising a downwardly directed portion through which material and air are discharged from the chamber and deflected in a downward direction, and an upwardly directed extension through which samples of material may be removed from the spout without the escape of air, and a cover attached to the top of the extension for normally closing the same.

2. In a pulverizer mill having grinding mechanism and a chamber adapted to receive the material after it has been pulverized, the combination of a discharge spout leading downwardly from the chamber and 80 through which material and air are discharged from the chamber, said spout being provided near its upper end with an upwardly directed extension through which samples of material may be removed from 85 the discharge spout, a lid attached to the upper end of the extension, and means connected to the lower end of the discharge spout for conveying pulverized material from the mill.

In testimony whereof I affix my signature.
JAMES W. FULLER.
